SINGLE TRIGGER MECHANISM

Harry Wareham, Chicopee Falls, Mass., assignor,
by mesne assignments, to Savage Arms Corporation,
Utica, N. Y., a corporation of Delaware

Application October 19, 1932, Serial No. 638,483

7 Claims. (Cl. 42—42)

My invention relates to double- or multiple-barreled shot guns. Its object is to provide an improved trigger mechanism wherein successive pulls on the same trigger serve to fire the barrels successively. More especially the invention provides an arrangement to this end which is applicable to standard or conventional gun designs without substantial change or re-arrangement of the existing elements thereof and which is extremely simple so as to add but little to the cost thereof, thereby permitting guns originally designed for multiple-trigger action in the usual way to be adapted readily to single-trigger action.

Speaking generally, my invention consists in using as the operating connection between the single trigger (or the trigger which fires the first barrel) and that portion of the firing mechanism which serves the barrel to be fired second, a main member located at one side of the firing mechanisms for both barrels which member has a projection or projections thereon or otherwise associated therewith, extending substantially transversely of the gun, and forming the intermediate connection to produce the desired functioning. Such placement of the main member permits it to be of plate-form and disposes the major part of the mechanism which is to be added to the standard design mainly at one side of, or outside of, the space occupied by the firing pins, hammers, hammer springs, and sears if any, where space can easily be made for it, while the interconnecting projections or other transverse members thereon will in most cases find room for operation in front or rear or under or over the existing parts of the firing mechanism without interfering with the proper functions of the latter.

The invention is exemplified in two embodiments in the accompanying drawings, in which: Fig. 1 is a perspective view of the frame portion of a break-down double-barreled shot gun to which my invention has been applied, the stock being removed and the parts being shown in the positions they occupy when both hammers are cocked. Fig. 2 is a side elevation of the same mechanism, but showing the parts in positions they occupy after the first barrel (here the right-hand barrel) has been fired, and before the pull on the trigger has been released. Fig. 3 is a section on line III—III of Fig. 2, in the direction of the arrows. Fig. 4 is an elevation similar to Fig. 2, but showing the parts in the positions they occupy after the trigger has been released. Fig. 5 is a similar elevation to show the parts in their

positions immediately following the firing of the second barrel the trigger being in its "pulled" position. Fig. 6 is a sectional plan view about on the line VI—VI of Fig. 1. Fig. 7 is a vertical section about on line VII—VII of Fig. 2. Fig. 8 is a perspective view illustrating another form of my invention as applied to a double-barreled shot gun, both hammers being shown cocked. Fig. 9 illustrates the parts immediately after the first barrel has been fired. Fig. 10 is similar to Fig. 9 excepting that the parts are in positions they occupy after the trigger has been released. Fig. 11 illustrates the positions of the same parts immediately after the second barrel has been fired.

Figs. 1 to 7 illustrate the invention applied to a standard form of double-barreled shot gun having a well known form of firing mechanism. The receiver or frame of the gun will be recognized at 1 and the barrels at 2, the latter being hinged to the frame at 3; also the top lever 4 for locking the gun closed, and the sliding safety thumb piece at 5. This particular form of safety piece functions by the action of the sliding thumb piece 5 swinging the nose 6 of the safety lever 7 over and away from the rear ends of the triggers 8 and 9 in a customary manner and as will be recognized from the drawings; any other type of safety might be used. Also as customary the reciprocating rod 10, connected to the lever 4, serves to push the safety to the "safe" position when the gun is broken.

The two triggers 8 and 9 are fulcrumed on the frame by a pivot pin 13; only one trigger 8 need be provided with the customary finger or pull piece 12 since the use of one trigger is to fire both barrels. Sear 14 and 15, hinged to the frame at 16, form the control connection between the two triggers 8 and 9 respectively and the two hammers or spring-pressed firing pins 17 and 18 respectively (herein called hammers) so that the upward movement of either trigger lifts its sear and fires the corresponding barrel; the spring 19 depresses both sears and through them presses the triggers toward their normal positions, in which they abut against the cross pin 20, all as customary.

The trigger 8 having the finger piece or pull 12 formed on it is arranged in permanent cooperating relation to the sear 14 and its hammer 17, i. e., the pull on this trigger always releases the (right-hand) hammer if it is cocked, although this action is not indispensable. By the effect of a plate member 24 this same trigger 8 may also release the lefthand hammer after the righthand

barrel has been fired. This plate 24 is located at one side of the firing mechanism, and is mounted movably in a longitudinal slot 24^a provided for it in one side of the frame 1; this slot serves to 5 guide and contain the plate being deep enough for the purpose. A pin held in the frame and passing through a slot 23 in the plate controls its forward end and keeps it from escaping from the frame-slot 24^a. This pin may be the end of the 10 trigger pivot pin 13. A spring 29, held to the frame by screw 31, acts to press the plate 24 forwardly; conveniently a pin or screw 32 is provided in the rear portion of the plate for the plate-end of the spring to rest against as shown 15 in Fig. 1. The plate 24 is thus arranged for forward and backward movement, and it may also turn or rock on its pin 13 in a vertical plane. A cross-pin 25 carried rigidly by the plate 24 and extending transversely thereof is arranged to enter 20 the notches 26 and 27 provided in the ends of the two triggers 8 and 9 when the plate 24 is allowed to move to its forward position (Fig. 4) and the triggers are in their normal positions, thus locking 25 the two triggers together, but while the plate 24 occupies its rearward position this cross pin 25 is entirely free of the trigger notches 26 and 27 (Fig. 1). The plate 24 also has another transverse projection 30 and which may be simply a bent-over tab on the body of the plate. This 30 member lies in the path of the hammer 17 of the first barrel to be fired.

The operation of the mechanism is evident from the foregoing. The breaking of the gun serves to 35 cock both hammers (by usual mechanism, not shown), and the cocking of hammer 17 engages the tab 30 and thereby pushes the plate 24 rearward against the thrust of spring 29 and the cross pin 25 is thus held clear of the notches 26 and 27 as long as hammer 17 remains cocked (Fig. 1). 40 A pull on the trigger 8 will now fire the righthand barrel. The spring 29 tends to thrust the plate 24 forward immediately the hammer 17 falls, but its pin 25 now abuts against the shoulder 35 of the trigger which prevents such movement 45 for the moment (Fig. 2). On releasing the pull on the trigger 8 the cross pin 25 enters the two trigger notches 26 and 27 thus locking them together (Fig. 4). A pull on the trigger 8 will now 50 lift the cross pin 25 with it (the plate 24 turning on its pin 13 and within its slot 24^a), and this lifts both triggers including trigger 9, and thereby 55 fires the second barrel (Fig. 5).

It will be apparent that the forms of the plate 24, the transverse members 25 and 30, the relation 55 of these and corresponding parts to each other and to the firing mechanism, the form of the firing mechanism, and the mechanism whereby the plate 24 is caused to move forward and back, are all subject to variation. Also, it is not essential 60 that triggers be locked together for the firing of the second barrel; other parts may be engaged to bring about firing of the second barrel. As an example of the latter, Figs. 8, 9, 10 and 11 illustrate an arrangement wherein a transverse 65 member corresponding to pin 25 coacts with the sears instead of the triggers. The gun of these figures is substantially the same as that of Fig. 1. The same frame 1, top lever 4, safety thumb piece 5, and spring-pressed hammers or firing pins 17 and 18, and sear spring 19 will be recognized. 70 The two sears are pivoted to the frame at 40 substantially as before. The sear 41 permanently relates the trigger 42 to the first hammer 17 to fall. The sear 43 cooperates with the second 75 hammer 18. The vertical plate 44 at the side of

the firing mechanism, its transverse member 45, spring 49, and second transverse portion 50 for cooperation with 47, are substantially like the corresponding parts 24, 25, 29 and 30 of the preceding figures. In the present instance however, 5 the transverse member or cross pin 45 is relocated, being placed immediately below the lower edges of the two sears 41 and 43, and the sear 41 of the first (righthand) barrel to be fired is provided with a notch 51 outside of which the cross pin 45 10 stands when the plate 44 is in its rearward position and which the pin 45 enters as the plate moves forward. Below the notch 51, a shoulder 52 serves the same purpose as the shoulder 35 of the preceding figures (Fig. 9). When the gun is 15 cocked initially the plate 44 is thrust to and held in its rearward position as before (Fig. 8). A pull on the trigger 42 now lifts only the sear 41, firing the righthand barrel and freeing the plate 44 at the transverse member 50; the shoulder 52 20 prevents forward movement of the plate for the moment however (Fig. 9). When the trigger is completely released the plate 44 moves forward and the cross pin enters the sear notch 51 (Fig. 25 10). A second pull on the trigger not only raises 25 sear 41 again, however, but also this sear now raises the cross pin 45 (tipping plate 44 on its mounting pin 13 as before), and the pin raises the sear 43, thus firing the second barrel (Fig. 11). A subsequent release of the trigger restores the 30 parts to their starting positions.

In general, it will be apparent that my invention is not limited to the details of construction and operation described above except as appears hereinafter in the claims. 35

I claim:—

1. In a multiple-barreled gun, the combination 40 with the firing mechanism thereof including a pair of hammers, spring means for throwing the latter, and a trigger, of a movable member located at one side laterally outwardly of one of said hammers with respect to the other of said hammers, means to hold said member in an initial position when all said hammers are cocked and to move said member to another position on the fall of one of said hammers, said movable member being arranged to effect an operating connection between said trigger and the other of said hammers on the movement of the member to said another position, and means to prevent 45 the movement of said movable member to said another position until the trigger has been substantially completely released after firing the first barrel.

2. In a multiple-barreled gun, the combination 55 with the firing mechanism thereof including a pair of hammers, spring means for throwing the latter, and a trigger, of a movable member mounted at one side laterally outwardly of one of said hammers with respect to the other of said hammers, means to hold said member in an initial position while all said hammers are cocked and to move said member to another position on the fall of one of the hammers, and a member 60 extending substantially transversely of the gun to cooperate with said movable member to make an operating connection between said trigger and the other of said hammers when said movable member stands in said another position.

3. In a multiple-barreled gun, the combination 65 with the firing mechanism thereof including a pair of hammers, spring means for throwing the latter, and a trigger, of a movable member mounted at one side laterally outwardly of 70

one of said hammers with respect to the other of said hammers, a spring to move said member to one position, a member extending substantially transversely of the gun to cooperate with one of said hammers and said movable member to hold the latter in another position against the thrust of said spring when said hammer is cocked, and a member extending substantially transversely of the gun to cooperate with said movable member to make an operating connection between said trigger and the other of said hammers when said member stands in its first mentioned position.

4. In a multiple-barreled gun, the combination with the frame and the firing mechanism thereof, said frame being provided with a longitudinally-extending slot in one of its vertically-extending walls and said firing mechanism including a plurality of hammers, spring means for throwing said hammers, and a trigger, of a member mounted in said slot in the frame and movable longitudinally of the gun therein, and means to hold said member in an initial position when all said hammers are cocked and to move said member substantially longitudinally of the gun on the fall of one of said hammers, said movable member being arranged to effect an operating connection between said trigger and another of said hammers on said movement of said member.

5. In a multiple-barreled gun, the combination with the firing mechanism thereof including a pair of hammers, spring means for throwing the latter, a sear for each hammer, and a trigger permanently cooperating with one of said sears, of a movable member mounted at one side laterally outwardly of one of said hammers with respect to the other of said hammers, means to hold said member in an initial position while all the hammers are cocked and to move said member to another position on the fall of one of said hammers, and a member extending substantially transversely of the gun to cooperate with said movable member to make an operating con-

nection between said one of the sears and another of said sears.

6. In a double-barreled gun, the combination with the frame and the firing mechanism thereof, said frame being provided with a longitudinally-extending slot in one of its vertically-extending side walls and said firing mechanism including two hammers, spring means for throwing said hammers individually, a trigger arranged to release one of said hammers, and mechanism to release the other of said hammers, of a member mounted in said slot in the frame for movement substantially vertically and substantially longitudinally of the gun, and a spring to move said movable member to a forward position, said movable member being provided with a substantially transverse projection for engagement by one of said hammers to move said movable member to its rearward position, and said movable member being provided with a projection extending substantially transversely of the gun to make an operating connection between said trigger and said hammer-releasing mechanism for said other hammer when said movable member stands in its forward position.

7. In a multiple-barreled gun, the combination with the frame and the firing mechanism thereof, one of the side walls of said frame being provided with a track, at one side of said firing mechanism, to carry the plate-like member hereinafter mentioned, and said firing mechanism including a plurality of hammers, spring means to throw the hammers, and a trigger, of a substantially flat plate-like member supported edge-wise in said track, and means to hold said member in an initial position when all said hammers are cocked and to move said member in said track substantially longitudinally of the gun on the fall of one of said hammers, means being provided, cooperative with said plate-like member, to effect an operating connection between said trigger and another of said hammers on said movement of said plate-like member.

HARRY WAREHAM.

CERTIFICATE OF CORRECTION.

Patent No. 2,052,957.

September 1, 1936.

HARRY WAREHAM.

It is hereby certified that error appears in the printed specification of the above numbered patent requiring correction as follows: Page 3, first column, line 18, claim 4, before "walls" insert the word side; and that the said Letters Patent should be read with this correction therein that the same may conform to the record of the case in the Patent Office.

Signed and sealed this 6th day of October, A. D. 1936.
